UNITED STATES PATENT OFFICE.

ARTHUR R. BILLINGTON, OF CHICAGO, ILLINOIS, ASSIGNOR TO THE STRAND MANUFACTORY COMPANY, OF CHICAGO, ILLINOIS, A CORPORATION OF ILLINOIS.

MACHINE FOR INTERWEAVING CURLLED HORSEHAIR.

1,243,133.

Specification of Letters Patent. Patented Oct. 16, 1917.

Application filed August 23, 1916. Serial No. 116,475.

To all whom it may concern:

Be it known that I, ARTHUR R. BILLINGTON, a citizen of the United States, residing at Chicago, in the county of Cook and State 5 of Illinois, have invented certain new and useful Improvements in Machines for Interweaving Curled Horsehair, of which the following is a specification.

This invention relates to improvements in 10 machines for interweaving curled horsehair, and has for one of its objects to provide an improved machine of this character whereby continuous sheets of fabric may be rapidly and quickly manufactured.

15 A further object is to provide an improved machine of this character which will be simple, durable and cheap in construction, and effective and efficient in operation.

To the attainment of these ends and the 20 accomplishment of other new and useful objects as will appear, the invention consists in the features of novelty in substantially the construction, combination, and arrangement of the several parts hereinafter more

25 fully described and claimed and shown in the accompanying drawings illustrating the invention, and in which;

Figure 1, is a side elevation of an improved machine of this character for carrying 30 this invention into operation.

Fig. 2, is a front elevation.

Fig. 3, is a detail view as taken on line 3—8 Fig. 2.

Fig. 4, is a top plan view of the parts 35 shown in Fig. 3.

Figs. 5, 6, 7, 8, 9, 10, 11, and 12, are views showing the different steps in the method of interweaving the material.

Referring more particularly to the drawings, the numeral 15 designates a support 40 of any desired size and configuration having guides 16 thereon through which the uprights 17 are adapted to freely slide. The uprights are connected by cross members 18, 45 19, forming a yoke and which yoke is given a vertical reciprocatory movement from a shaft 20, journaled in the supporting structure, and a connection between the shaft and the yoke, preferably by means of an eccentric 50 22. If desired one of these connections may be arranged on each side of the machine.

A plurality of needles 23, are connected to the yoke, preferably to the cross member

19 thereof, and each needle is provided with 55 an upwardly opening hook 24. At predetermined intervals in the operation of the machine the needles are given a rotary motion for a purpose to be hereinafter set forth, and this is accomplished preferably by 60 means of a pinion 25, secured to each needle, and with which pinions, a slideable rack 26, meshes, so that when the rack is shifted, the needles will be correspondingly rotated.

This shifting of the rack is preferably 65 accomplished by means of a projection or cam surface 27, adjustably secured to a fixed support, and which surface is adapted to be engaged by an end 28, of the rack, or an anti-friction roller journaled at that end, to shift 70 the rack against the tension of an elastic member 29, which latter returns the rack after it passes out of engagement with the cam surface, and thus the needles will be rotated first in one direction and then in 75 the opposite direction. Obviously, power is supplied to the shaft 20 from any suitable source.

The material 30, is supplied in any suitable manner to the feed rolls 31, 32, to be 80 compressed thereby and then advanced to the rolls 33, 34, the latter being preferably in the form of spaced disks, and between adjacent pairs of disks, the needles are adapted to be reciprocated to interweave the material. From the rolls 33, 34, the finished fabric is delivered to rolls 35, 36, and from 85 there out of the machine.

Motion is imparted to the rolls in any suitable manner, here shown as by means of a 90 ratchet gear 37, connected with the shaft of the disk roll 33, and a pawl 38 connected with an arm 39.

A bar 40 to which the arm is pivotally connected, reciprocates through a suitable 95 guide in the supporting structure, and is limited in its movement in one direction by an adjustable collar 41, which also serves as a means whereby the extent of feeding movement of the material may be varied, by varying 100 the extent of movement of the rolls.

The end of the rod 40, is arranged in the path of movement of the cross member 18, of the yoke, upon its upward movement, and each time the ratchet is operated, the feed 105 roll will be moved.

The rolls 31, 36, and 32, 35, receive their motion respectively from the rolls 34, 33, as

by sprocket chains 42, 43, and the disk rolls 33, 34, may be operatively connected by gears 44, 45.

Thus it will be seen that each time the 5 yoke is reciprocated, the cross member 18, thereof when moving in one direction, will engage and shift the bar 40 and impart one step of rotation to all of the feed rolls, to advance the material across the path of 10 movement of the needles.

The operation of this invention, briefly stated is as follows:

Each time the needles are lowered, a rotary motion will be imparted thereto in one 15 direction, and each time they are elevated, a rotary motion will be given to them in the opposite direction.

The material being intermittently fed 20 across the path of the reciprocatory movement of the needles, each time the needles are lowered, the material will be penetrated by the needles. After the needles have entered the material, a rotary movement will be given the needles, so that when they are 25 raised they will grasp some of the material from beneath the surface of the material, and draw it through the body of the material to form a loop, see Figs. 5, and 6.

During the rising movement of the 30 needles, they are given a rotary movement, and the material is then advanced by the feed rolls. By rotating the needles, the loop is given a twist, and the loop will be held upon the needle during its downward movement so that the needle will be moved 35 through the loop. After the needle again penetrates the material, it is given another rotary motion and then raised, so that the needle will draw another portion of the material with it through the loop already 40 formed to interweave that portion just drawn from the material into a new loop, with the old loop just previously formed, as shown clearly in Figs. 7 to 12.

45 This operation is repeated during the entire time that the material is being advanced by the feed rolls.

By rotating the needles, the material is 50 prevented from dropping off of the needles during their lowering movements and the old loop will not be picked up by the needles on their upward movements.

If it is desired to obtain merely a tufting 55 operation, all that is necessary is to hold the needles against rotary movement, and this can be accomplished by simply removing the cam surface 27, or adjusting it to a position that it will not be engaged by the end of the rack bar 26.

60 What is claimed as new is:

1. A machine of the character described 65 embodying mechanism for feeding a bat of material, a reciprocatory needle, means for reciprocating the needle to cause the needle to impale the material and to withdraw

therefrom to draw a portion of the material partially from the bat, and means for axially rotating the needle after withdrawal.

2. A machine of the character described 70 embodying mechanism for feeding a bat of material, a reciprocatory needle, means for reciprocating the needle to cause the needle to impale the material and to be withdrawn therefrom to draw a portion of the material partially from the bat, means for axially rotating the needle after withdrawal, the said feeding mechanism embodying means responsive to the reciprocation of the needle for intermittently actuating the said mechanism.

3. A machine of the character described 75 embodying a reciprocatory needle having an upwardly opening hooked shaped portion, mechanism for feeding a bat of material across the path of movement of the needle, 80 said needle being adapted to impale the material and to be withdrawn therefrom to grasp and draw a portion of the material from below the upper surface thereof, partially from the material to form a loop, and 85 means for axially rotating the needle while in engagement with the loop to twist the loop and through which loop the needle is reciprocated.

4. A machine of the character described 90 embodying a reciprocatory needle having an upwardly opening hooked shaped portion, mechanism for feeding a bat of material across the path of movement of the needle, 95 said needle being adapted to impale the material and to be withdrawn therefrom to grasp and draw a portion of the material from below the upper surface thereof, partially from the material to form a loop, 100 means for axially rotating the needle while in engagement with the loop to twist the loop and through which loop the needle is reciprocated, and provisions embodying the 105 last recited means for rotating the needle in the opposite direction to position the 110 hooked shaped portion to pass through the previously formed loop without engaging the loop.

5. A machine of the character described 115 embodying a plurality of parallel reciprocatory needles, means for feeding a bat of material across the path of reciprocation of the needles and embodying coöperating rolls each embodying spaced coöperating pairs of disks, said needles being adapted to be reciprocated between adjacent pairs of disks, to impale the material and to be withdrawn therefrom, to draw a portion of the material partially from the bat, means for axially 120 rotating the needle after withdrawal, and means for intermittently actuating the disks to feed the material.

6. A machine of the character described 125 embodying a plurality of parallel reciprocatory needles, means for feeding a bat of 130

- material across the path of reciprocation of the needles and embodying coöperating rolls each embodying spaced coöperating pairs of disks, said needles being adapted to be reciprocated between adjacent pairs of disks to impale the material and to be withdrawn therefrom, means for intermittently actuating the disks to feed the material, said needles having an upwardly opening hooked shaped portion to engage and partially withdraw a portion of the material from the bat, and means for imparting an axial rotation to the needles to twist the withdrawn portion of the material.
7. A machine of the character described embodying a plurality of parallel reciprocating needles, means for feeding a bat of material across the path of reciprocation of the needles and embodying coöperating rolls each of which embodies spaced coöperating pairs of disks, said needles being adapted to be reciprocated between adjacent pairs of disks to impale the material and to be withdrawn therefrom, means for intermittently actuating the disks to feed the material, said needles having an upwardly opening hook shaped portion to engage and partially withdraw a portion of the material from the bat, and means for axially rotating the needles in one direction to twist the withdrawn portion of the material to form a loop through which the needle is adapted to be reciprocated, to withdraw another portion of the material through the loop, the last said means also operating to axially rotate the needles in the opposite direction.
8. The method of interweaving curled horse hair, which consists in feeding a bat of material across the path of a reciprocating needle, then reciprocating the needle to cause the same to impale the material and withdraw a portion of the material partially from the supply to form a loop, then twisting the needle to cause the loop to be twisted, then moving the needle through the loop in one direction to again impale the material, then twisting the needle into a position that it may be withdrawn from the loop, then withdrawing the needle from the supply to draw another portion of the supply partially from the supply and through the previously formed loop, and finally causing the needle and the material to be laterally displaced one with relation to the other.
9. In testimony whereof I have signed my name to this specification, in the presence of two subscribing witnesses, on this 19th day of August, A. D. 1916.
- ARTHUR R. BILLINGTON.
